MACHINERY FOR DRESSING ORE

Frank Edwin Draper, Greig Flats, via Pambula, New South Wales, Australia, assignor to Draper Multi-Disc Mining Processes Pty. Limited, Sydney, Australia

Filed June 7, 1960, Ser. No. 34,557

Claims priority, application Australia June 29, 1959
7 Claims. (Cl. 241—107)

This invention relates to machinery for the concentrating of minerals contained in ore and especially for minerals finely dispersed in a matrix and which have to be recovered subsequently as fine dust, either by the known mechanical process of flotation or the heavy-light system in moving water or by a chemical process.

The mechanical process in use requires a multiplicity and a variety of machines according to the physical state of the ore. After being crushed to reduce the ore to a size around $\frac{1}{2}$ " there are needed rolls, ball-mills with classifiers, flotation cells and settling tanks. All this apparatus has to be linked by pipes and pumps, and positioned in the right place on scaffolding and requires attendance, maintenance and supervision.

The object of this invention is to incorporate in one machine treatment from an ore-pebble size of about $\frac{1}{2}$ " down to the finished concentrate of a screen size of about 200 mesh. This means the combination of machinery necessary to extract a concentrate of the desired mineral from the ore and to separate the gangue, to be either discarded or to be further treated for mineral components.

The invention in a general form is an ore dressing mill comprising a continuous channel, the channel floor having a substantially flat smooth surface, a series of circumferentially spaced groups of independently rotatable crushing rollers in the channel, the rollers of each group being radially spaced flat discs, means for moving the groups around the channel, the rollers of each group being staggered radially in relation to those of other groups to ensure that ore in the channel is crushed between the rollers and the wearing strip for the full channel width, means for feeding ore to the channel, means for feeding water to the channel, means for withdrawing water and selected fines from the channel at selected levels and means for withdrawing wet concentrates from the channel.

One form of the invention will now be described with reference to the accompanying drawings in which:

FIGURE 1 is a fragmentary plan view of one form of the invention with certain parts omitted for clarity;

FIGURE 2 is a fragmentary vertical diametral section of FIGURE 1;

FIGURE 3 is an enlarged view showing a section of the channel on line 3—3 of FIGURE 1;

FIGURE 4 is a further enlargement corresponding to FIGURE 3 but for clockwise rotation;

FIGURE 5 is a sectional elevation on the line 5—5 of FIGURE 4;

FIGURE 6 is a radial vertical section on line 6—6 of FIGURE 1 showing the driving means;

FIGURE 7 is a side sectional elevation on the line 7—7 of FIGURE 4 showing the mechanism for controlling the liquid discharge pipe shown at the right hand side of FIGURE 4, and

FIGURE 8 is a view showing the means for feeding ore to the channel.

Referring to FIGURES 1 to 8, the channel 13 is of reinforced concrete and has an outer wall 14, an inner wall 15 and a floor 16. The floor has a manganese steel lining or wearing strip 17. One or more openings 18 are formed through the floor and each may be covered by a grid 19. Above each grid is a removable section 17a of the lining 17. The joint between the section 17a

2

and the floor is made watertight. One or more L-shaped outlet pipes 20 open at each end are circumferentially spaced around the inner wall 15. The horizontal leg 22 of each pipe is rotatably mounted in a liquid tight bush 23 fitted tightly in a passage through the wall and the vertical leg 24 of the pipe is located in a recess 25 in the inside of the wall. The pipe may be rotated about the axis of its leg 22 by means of a lever 21. In this way the height of the inlet end of the leg 24 can be varied and with it the liquid level in the channel.

A shallow pan bounded by the inner wall 15 has a floor 26 integral with the channel, the top level of the floor 26 being below the level of the floor 16. A valved outlet 27 through the floor 26 is provided at its lowest point.

A central hub or post 28 is located at the centre of the floor 26. Sixteen sets 29 of discs and axles are equally spaced around the circumference of the channel 13 with the discs resting on the floor of the channel.

Each axle 30 has independently rotatably mounted on it similar cast iron discs 31 with manganese steel tires 31a. Each disc has two integral half spacers 32 which separate the discs. Each axle end passes through a hole 33 in one end of an arm 34 pin-connected at its other end to a bracket 35 mounted on a ring 41 connected to the outer end of a spider arm 36. The inner ends of the arm 36 are connected to a collar 37 rotatably mounted on suitable bearings on the upper end of the hub 28. Paddles 36a suspended from the spider arms 36 keep slimes in the pan 26 in suspension. Circumferential spaced pedestals 38 are mounted on and around each wall 14, 15. Each pedestal carries a rotatable jockey roller 39. Each line of rollers supports a flat inner ring 40 or outer ring 41. The ring 41 carries a rack 42 meshing with a pinion 43 driven through gears by a motor 44. The rings 40, 41 also carry the brackets 35 to which the other ends of the arms 34 are pin-connected. The outer ends of the spider arms 36 are also connected to the rings 40, 41.

Each end of each axle has loosely mounted on it a plough arm 46 which carries on its other end a trailing ploughshare 47 which rests on the channel floor and continually scrapes material being treated from the channel sides towards the centre.

An important feature of the invention is that corresponding discs of adjacent sets 29 are relatively displaced radially so that as far as practicable the whole area of the channel is covered radially by one group of four axles carrying five discs each.

FIGURE 2 is a fragmentary vertical diametral section of FIGURE 1 showing the driving means; FIGURE 3 is an enlarged view showing a section of the channel on line 3—3 of FIGURE 1; FIGURE 4 is a further enlargement corresponding to FIGURE 3 but for clockwise rotation; FIGURE 5 is a sectional elevation on the line 5—5 of FIGURE 4; FIGURE 6 is a radial vertical section on line 6—6 of FIGURE 1 showing the driving means; FIGURE 7 is a side sectional elevation on the line 7—7 of FIGURE 4 showing the mechanism for controlling the liquid discharge pipe shown at the right hand side of FIGURE 4, and FIGURE 8 is a view showing the means for feeding ore to the channel.

Referring to FIGURES 1 to 8, the channel 13 is of reinforced concrete and has an outer wall 14, an inner wall 15 and a floor 16. The floor has a manganese steel lining or wearing strip 17. One or more openings 18 are formed through the floor and each may be covered by a grid 19. Above each grid is a removable section 17a of the lining 17. The joint between the section 17a

and the floor is made watertight. One or more L-shaped outlet pipes 20 open at each end are circumferentially spaced around the inner wall 15. The horizontal leg 22 of each pipe is rotatably mounted in a liquid tight bush 23 fitted tightly in a passage through the wall and the vertical leg 24 of the pipe is located in a recess 25 in the inside of the wall. The pipe may be rotated about the axis of its leg 22 by means of a lever 21. In this way the height of the inlet end of the leg 24 can be varied and with it the liquid level in the channel.

A shallow pan bounded by the inner wall 15 has a floor 26 integral with the channel, the top level of the floor 26 being below the level of the floor 16. A valved outlet 27 through the floor 26 is provided at its lowest point.

A central hub or post 28 is located at the centre of the floor 26. Sixteen sets 29 of discs and axles are equally spaced around the circumference of the channel 13 with the discs resting on the floor of the channel.

Each axle 30 has independently rotatably mounted on it similar cast iron discs 31 with manganese steel tires 31a. Each disc has two integral half spacers 32 which separate the discs. Each axle end passes through a hole 33 in one end of an arm 34 pin-connected at its other end to a bracket 35 mounted on a ring 41 connected to the outer end of a spider arm 36. The inner ends of the arm 36 are connected to a collar 37 rotatably mounted on suitable bearings on the upper end of the hub 28. Paddles 36a suspended from the spider arms 36 keep slimes in the pan 26 in suspension. Circumferential spaced pedestals 38 are mounted on and around each wall 14, 15. Each pedestal carries a rotatable jockey roller 39. Each line of rollers supports a flat inner ring 40 or outer ring 41. The ring 41 carries a rack 42 meshing with a pinion 43 driven through gears by a motor 44. The rings 40, 41 also carry the brackets 35 to which the other ends of the arms 34 are pin-connected. The outer ends of the spider arms 36 are also connected to the rings 40, 41.

Each end of each axle has loosely mounted on it a plough arm 46 which carries on its other end a trailing ploughshare 47 which rests on the channel floor and continually scrapes material being treated from the channel sides towards the centre.

An important feature of the invention is that corresponding discs of adjacent sets 29 are relatively displaced radially so that as far as practicable the whole area of the channel is covered radially by one group of four axles carrying five discs each.

FIGURE 2 is a fragmentary vertical diametral section of FIGURE 1 showing the driving means; FIGURE 3 is an enlarged view showing a section of the channel on line 3—3 of FIGURE 1; FIGURE 4 is a further enlargement corresponding to FIGURE 3 but for clockwise rotation; FIGURE 5 is a sectional elevation on the line 5—5 of FIGURE 4; FIGURE 6 is a radial vertical section on line 6—6 of FIGURE 1 showing the driving means; FIGURE 7 is a side sectional elevation on the line 7—7 of FIGURE 4 showing the mechanism for controlling the liquid discharge pipe shown at the right hand side of FIGURE 4, and FIGURE 8 is a view showing the means for feeding ore to the channel.

Referring to FIGURES 1 to 8, the channel 13 is of reinforced concrete and has an outer wall 14, an inner wall 15 and a floor 16. The floor has a manganese steel lining or wearing strip 17. One or more openings 18 are formed through the floor and each may be covered by a grid 19. Above each grid is a removable section 17a of the lining 17. The joint between the section 17a

disintegration of the ore has been achieved the water containing fine slimes in suspension is run off by turning the pipe 20 until its inlet end is below the liquid level. The slimes accumulate in the pan and are kept in suspension by the paddles 36A carried by the arm 36. The slurry in the pan can be run off through the passage 27 at intervals, either to waste or for further treatment.

The heavier material mixing with the water in the channel 13 can be removed at intervals by lifting sections 17A covering the grids 18 and permitting the mixture of heavy material and water to flow away. The mixture can then be subjected to further treatment.

In a modification the arms 36 may be eliminated and circumferentially spaced radial straps provided to hold the tracks 40, 41 together. For correctly locating the tracks, rollers on vertical axles are spaced along and bear against the inner edge of the inner track, 40.

The track connecting straps also serve to support the hoppers 48. A limited number of radial arms 36 may still be required, supported at 37 and on 40, 41, to carry the stirring paddles 36A.

An alternative means for moving the rollers is to provide fixed rails on the channel walls instead of the tracks 40, 41 and to run on the rails one or more motor driven trolleys, each of which tows one or more groups of rollers.

For dry crushing ores the means for feeding water and removing water, selected fines and wet concentrates are not required.

In an alternative means for feeding ore to the channel there are provided a bulk storage bin, a conveyor belt, a fixed bin below the conveyor at one point and moveable bins supported on the tracks and extending into the channel. Spaced vertical deflectors immediately above the belt and above the fixed bin distribute ore to be crushed from the conveyor into the fixed bin and along its length. The bottom of the fixed bin is closed by a counter weighted door and the bin is located above the channel with the counter weighted end in the path of a trip or cam carried on each moveable bin. As each moveable bin reaches the fixed bin, the door of the latter is opened and ore passes into the moveable bin.

Each moveable bin may be located, for example, between adjacent groups of rollers. Its bottom is similarly movably closed by a counter weighted door which is automatically opened at intervals as required by cam means as before.

What I claim is:

1. An ore dressing mill comprising a continuous channel, the channel floor having a substantially flat smooth surface, a series of circumferentially spaced groups of independently rotatable crushing rollers in the channel,

the rollers of each group being radially spaced flat discs, means for moving the groups around the channel, the rollers of each group being staggered radially in relation to those of other groups to ensure that ore in the channel is crushed between the rollers and the wearing strip for the full channel width, means for feeding ore to the channel, means for feeding water to the channel, means for withdrawing water and selected fines from the channel at selected levels and means for withdrawing wet concentrates from the channel.

2. A mill as in claim 1 wherein each group of discs is connected to the group moving means so as to permit up and down movement of the group as it passes around the channel.

3. A mill as in claim 1 wherein the channel is circular and has radially spaced walls, each group of disc rollers comprises radially spaced discs on a radial axle and the group moving means comprise ring tracks rotatably supported on the respective channel walls, each axle being linked at its respective ends to the tracks and means for rotating the tracks.

4. A mill as in claim 3 wherein the means for rotating the tracks include a rack secured to at least one of the tracks, a fixed pinion meshing with the rack and means for rotating the pinion.

5. A mill as in claim 3 wherein each axle is linked to the respective tracks by similar spaced arms, each pivotally connected at one end to the axle near one end and near its other end to the corresponding track.

6. A mill as in claim 1 wherein the water and fines withdrawing means comprise a recess in the inside face of one channel wall, an approximately horizontal passage leading through the wall from the recess to outside the wall, an L shaped pipe with one leg in the recess and the other leg rotatably mounted in the passage in substantially fluid tight fashion and means for rotating the pipe about the axis of the passage.

7. A mill as in claim 1 wherein the means for withdrawing water and concentrates includes one or more passages below the channel floor, and a removable section of the floor above each passage.
